DESIGN FOR A CASE FOR METERS OR SIMILAR ARTICLE

Robert T. Oelrich, Chicago, Ill.

Application July 29, 1944, Serial No. 114,626

Term of patent 14 years

(Cl. D52—2)

To all whom it may concern:

Be it known that I, Robert T. Oelrich, a citizen of the United States, residing at Chicago, in the County of Cook and State of Illinois, have invented a new, original, and ornamental Design for a Case for Meters or Similar Article, of which the following is a specification, reference being had to the accompanying drawing, forming part hereof.

Figure 1 is a front elevational view of a case

for meters, or similar article, showing my new design,

Figure 2 is a side elevational view,

Figure 3 is a top plan view, and

Figure 4 is a bottom plan view thereof.

I claim:

The ornamental design for a case for meters, or similar article, as shown.

ROBERT T. OELRICH.
